Primary Examiner — Catherine A Tuttle(74) *Attorney, Agent, or Firm* — Foley & Lardner LLP(57) **CLAIM**

The ornamental design for a bottle, as shown and described.

DESCRIPTION

FIG. 1 is a top perspective view of the claimed design;
 FIG. 2 is a front view thereof;
 FIG. 3 is a rear view thereof;
 FIG. 4 is a left side view thereof;
 FIG. 5 is a right side view thereof;
 FIG. 6 is a top view thereof; and,
 FIG. 7 is a bottom view thereof.

The broken lines formed by equal length dashes depict the bottom end profiles that form no part of the claimed design. The broken lines formed by alternating length dashes represent the lower boundary of the claim, but are themselves unclaimed.
